PIGMENT CONDITIONER

Orla R. Plummer, Napoleon, Ohio

Application March 18, 1940, Serial No. 324,644

3 Claims. (Cl. 259—39)

This invention relates to painting or coating material treatment toward uniformity of body for application even by spraying.

This invention has utility in motive-fluid-operable spray equipment in conjunction with an agitator in the supply for such equipment as operated by motive fluid.

Referring to the drawings:

Fig. 1 is a side elevation of a conditioner or agitator, parts being broken away;

Fig. 2 is a plan view of the container or agitator tank, showing the head mounting elements of the unit;

Fig. 3 is a detail view in plan of the double acting fluid motor;

Fig. 4 is a view of the motor from the left of Fig. 3;

Fig. 5 is a section on the line V—V, Fig. 3, showing the transmission from the motor;

Fig. 6 is a detail view of the lower portion of the stirrer and its connection to the drive;

Fig. 7 is a section on the line VII—VII, Fig. 6, showing the weave or twist in the stirrer blade, and its mounting;

Fig. 8 is a view of the motor from the right of Fig. 4;

Fig. 9 is a section of the motor on the line IX—IX, Fig. 8; and

Fig. 10 is a section on the line X—X, Fig. 1, showing the relation of the stirrer elements to the container.

Electric motor 1 is connected to drive compressor 2 (Fig. 1) for supplying compressed air through duct 3 to fitting 4 on head 5 of a container or seamless tank having bottom 6 and cylindrical side walls 7. These side walls 7 carry brackets 8 from which swing arms 9 having wing screws 10 (Figs. 1, 2) for engaging with flange 11 in compressing gasket 12 into sealing position at upper opening or top 13 of this container. This top 5 has thereon air gage 14, safety valve 15, filler opening 16 with removable cap 17, and relief cock 18, which may be operated to relieve any internal pressure before removing the cap 17 for filling through the opening 16 of additional pigment 19 into the vessel or tank. This fitting 4 has line 20 therefrom in communication with the interior of this vessel or tank to establish pressure in region 21 above the pigment 19 as controlled by pressure reduction valve 22. From this fitting 4 line 23 extends to grip 24 for air to spray gun 25. Central flange 26 of this top or head 5 of the container has a plurality of outlets 27. Valve 28 therein is effective for con-

nected line 29 as the pigment supply to the gun 25.

The flange 26 (Fig. 5) has internally threaded portion 30, with which is connected tube 31. Concentrically with this tube 31, this flange 26 has shaft 32 therethrough with gland packing 33 therefor. This shaft 32 as extending concentrically through the tube 31 has key 34 (Fig. 6) for anchoring port-carrying disk 35 with this shaft 32. This ported disk 35 has fixed therewith downward flare chamber 36 to open bottom 37. From this hub flare portion 36 radial arms extend of inverted T-form having upstanding flange 38 and bottom 39. These have clearance 40 from the bottom 6 of the tank.

Bolts 41, in the upstanding flange 38 of the radiating arms, anchor straps 42 having 45° pitch or twist therein as ascending to frame 43 (Figs. 1, 10) with straight portion 44 upward therefrom to top frame 45. This upper work is 20 a skeleton with full clearance as to the frames 43, 45, from the tube 31. The entire mounting is at the base of the tube at the perforate washer 35 with the upper portion of the flare, providing bearing 46 with the lower terminus of the tube 25 31. Accordingly, in rotation or alternating rotary motion of this shaft 32, the actuation is of the stirrer for the blades 38 to have a pick-up similarly in each direction of rotation. A weave of 45° in the upwardly extending straps 42 tends 30 to establish a direction of flow or circulation in the body as initiated from the radial blade 38. In the instance this direction of flow promotion be for elevating or lifting the pigment, at once there is reversal of the direction of rotation, the 35 counter-flow or down action is effected. In practice, this has meant with the minimum of energy applied that there is an efficient agitation or stirring for producing uniformity in the material 19 even as against tendencies for precipitation or 40 separation.

Efficiency for spray painting equipment use is obtained in that the motive fluid for the spray gun may, from the same power source, be the motive fluid to operate this stirrer which has 45 been effective with consumption of but three cubic feet per minute in a tank of as much as seventy-five gallons capacity and having pigment at least as much as half full therein.

To such end, from this fitting 4 line 47 (Fig. 4) 50 extends past valve 48 to line 49 to port 50 in cylinder body 51 (Fig. 9). From this port 50 there is duct 52 extending to port 53 (Figs. 8, 9) at the opposite end of the housing 51. This is accordingly a fluid pressure supply as adjusted 55

by the valve 48. This body 51 provides slide valve ways 54, 55, in alignment. From the port 59 there is valve port 56 which may be shut off by bar 57 locating cut-out 58 away from port 59. 5 At this position away from the port 59 the bar 57 may be so located that the port 59 is in exhaust position or open to the atmosphere as to cylinder 60 in the body 51. At this time the bar 57 is so located that port 61 from the port 53 10 is in communication through cut-out 62 with port 63 for pressure fluid supply to cylinder 64 as the cylinder 60 is exhausted. The slide valve bar 57 is yieldably held seated by U-shaped spring members 65 in notches 66 of the housing 15 51 and notches 67 of the bar 57. This bar or slide valve 57 has anchored thereto by screws 68 an actuator plate 69 having a downwardly extending tip or tongue 70 (Fig. 5) extending through opening 71 in the housing 51 between 20 the cylinders 60 and 64.

In the cylinder 60 is piston 72 from which extends piston rod or bar 73 to piston 74 in the cylinder 64. Bolts 75 assemble cylinder head 76 against packing 77 for sealing the cylinder 64. 25 Mounted on the cylinder rod or bar 73 by screws 78 is member 79 having terminal upstanding ears 80 which, as the piston 72 is at the inward limit of stroke, strikes the tongue 70 for thereby shifting the slide valve bar 57 in reversing the air 30 flow or motive fluid for this motor. In the reverse travel of the piston 72 having rings 72', as the piston 74 with its rings 74' recovers from its position near the head 76 to the remote position therefrom, then the upstanding ear 80 adjacent the piston 74 strikes the tongue 70 to shift the bar 57 for motive fluid counterflow, that is, 35 exhausting of the cylinder 64 and motive fluid supply to the cylinder 60.

Fixed with this bar 73, 79, is rack bar 81 in 40 mesh with pinion 82, the extent of reciprocation of this rack being such as to turn the pinion 82 herein less than a full rotation. This pinion 82 is integral with sleeve 83 (Fig. 5) having spline 84 engaging with the shaft 32. Set screw 85 may 45 further anchor this sleeve and pinion in its rotation with the shaft 32 and against longitudinal movement relatively one to the other.

This body 51 between the cylinders 60, 63, has 50 below the rack intermediate body portion 86 which may be engaged by bolts 87 of U-shaped bracket 88 having its feet 89 (Fig. 1) anchored by bolts 90 with the head 5. This body 51 is accordingly firmly supported on the head and has therein about the shaft 32 bushing 91 (Fig. 5) carrying anti-friction thrust bearing 92 against the lower side of the sleeve 83 as a support for this stirrer mechanism. Screws 93 mount sleeve 94 carrying anti-friction roller bearing 95 as a lateral support for the shaft 32 above 60 the sleeve 83.

This body intermediate portion 86 of the motor frame has chamber 96 therein, from which extends pipe 97 having upstanding filler opening 98 (Fig. 8) which may be closed by cap 99. In 65 supplying lubricant to this filler opening 98, lubricant 100 in the chamber 96 is thus above the bottom of the cylinders 60, 64, and in cylinder reciprocation is effective lubrication for such cylinders, but with the pressure in these single 70 acting cylinders from the one side only, the liquid is normally blown out of the cylinders back into the intermediate chamber 96 for lubricating the cylinders, rack and pinion. There is thus an efficient lubrication in a simplified construction. The slide valve is simply mounted and

yieldably held in position. As so disposed, housing plate 101 anchored by screws 102 with this main body 51 is an efficient assembly against casual disturbance in operation hereunder. To remove the cap or top, the flexible ducts therefrom are no interference. The cap or top may be lifted out with the tube 31 therewith. In the event the set screw 85 be slackened, the transmission mechanism and shaft 32 may be left in the vessel, while if the set screw 85 be in lock position, the stirrer unit may be taken therefrom and the tank thus be entirely clear for removal or substitute material or other care charge. Projecting knurled stem 103 (Fig. 5) fixed with the bar 57 permits manual shifting for locating 15 the valves in proper starting position.

In the operation hereunder, this tank 7 may be charged with the coating material to the extent desired, the top 5 clamped in position thereon, and the flexible tubes 3, 23, 29, in connection 20 from the pressure supply to the spray gun 25. With the head 5 clamped into sealing position by the wing screws 10, the valves may be manipulated for the desired pressure in the portion 21 of the container, thus to promote flow upward in 25 the tube 31 in lieu of having induction action at the gun sufficient to draw such up. Accordingly, this regulation may be in keeping with the desired quantity of material to be used. Adjustment of the valve 48 may be for such rate of 30 reciprocation as may be desired for this motive fluid motor of the stirrer or agitator. As this motor operates, say a clockwise turn may cause the material to flow toward the bottom. Its immediate reversal is a counter-turn for such material to flow upward in addition to the circulatory flow. The compound action is efficient for uniform distribution of the solids in the material so that such material as in the clearance region 35 40 below the arms 38 may work upward into the 40 flare 36 and by way of the tube 31 about the shaft 32 to be discharged by the duct 27 with the rate of flow cut-off determined by the valve 28 with the further adjustment at the spray gun 25.

What is claimed and it is desired to secure by 45 United States Letters Patent is:

1. In pigment conditioners for combination with spray equipment, a receptacle, a closure for sealing the receptacle, a central upwardly-directed discharge duct fixed with the closure, 50 said duct being provided with an intake opening near the bottom of the receptacle, a drive shaft housed by the duct to extend toward the intake opening of the duct, a stirrer in the receptacle adjacent the intake opening to the duct, connecting means for the stirrer to the shaft, a pressure fluid supply to the receptacle exterior of the discharge duct, and discharge means providing a passage from the duct adjacent the closure, whereby said fluid supply to the sealed 60 receptacle may effect upward flow of pigment or liquid charge in the receptacle as submerging the duct intake to flow through said duct intake upward in the duct about the shaft, and therefrom through the discharge means. 65

2. In pigment conditioners for combination with spray equipment, a receptacle, a closure for sealing the receptacle, a central upwardly-directed discharge duct fixed with the closure, said duct being provided with an intake opening near the bottom of the receptacle, a shaft housed by the duct to extend toward the intake opening of the duct, alternating rotary drive means for the shaft to agitate pigment carrying material as submerging the duct intake opening, a stirrer in 70 75

the receptacle adjacent the intake opening to the duct, connecting means for the stirrer to the shaft, a pressure fluid supply to the receptacle exterior of the discharge duct, and discharge means providing a passage from the duct adjacent the closure, whereby said fluid supply to the sealed receptacle may effect upward flow of pigment material charge in the receptacle as submerging the duct intake to flow through said duct intake upward in the duct about the shaft, and therefrom through the discharge means.

3. In pigment conditioners for combination with spray equipment, a receptacle, a closure for sealing the receptacle, a central upwardly-directed discharge duct fixed with the closure, said duct being provided with an intake opening near the bottom of the receptacle, a shaft housed by the duct to extend toward the intake opening of

the duct, alternating rotary drive means for the shaft to agitate pigment carrying material as submerging the duct intake opening, a stirrer in the receptacle adjacent the intake opening to the duct, said stirrer comprising upwardly extending arms having an axially extending pitch in the lower portion thereof, connecting means for the stirrer to the shaft, a pressure fluid supply to the receptacle exterior of the discharge duct, and discharge means providing a passage from the duct adjacent the closure, whereby said fluid supply to the sealed receptacle may effect upward flow of pigment material charge in the receptacle as submerging the duct intake to flow through said duct intake upward in the duct about the shaft, and therefrom through the discharge means.

ORLA R. PLUMMER.
